DESIGN FOR A FINGER RING

Meryl L. Stoddard, Davison, Mich., assignor of one-half to Valentine W. Krenzer, Ann Arbor, Mich.

Application July 23, 1941, Serial No. 102,399

Term of patent 3½ years

To all whom it may concern:

Be it known that I, Meryl L. Stoddard, a citizen of the United States and a resident of Davison, in the county of Genesee and State of Michigan, have invented a new, original, and ornamental Design for Finger Rings, of which the following is a specification, reference being had to the accompanying drawing, forming a part thereof.

The characteristic features of my design reside in the portions of the ring shown in full lines.

I claim:

The ornamental design for a finger ring, as shown and described.

MERYL L. STODDARD.
